UNITED STATES PATENT OFFICE

ROY W. SCHWEIKER, OF LANSDALE, PENNSYLVANIA

SIDE WALL LIGHTING FIXTURE

Application filed December 29, 1925. Serial No. 78,122.

This invention relates to side wall lighting fixtures, particularly those which are of porcelain and intended for use in kitchens, bath rooms and lavatories where persons operating the fixture are liable to grasp the key, or switch operating device while also grasping a metal water fitting or when in a bath, and thus be liable to electrical shock.

The object of the invention is to provide a side wall lighting fixture, preferably of porcelain, and particularly intended for use in kitchens, bath rooms and lavatories, in which the operating means for the switch is entirely covered and protected by the porcelain or other insulating material comprising the fixture; further, to provide a side wall lighting fixture of that general type employing an operating piece, pendant or lever, which is mounted in a "universal" manner so as to be adapted to be operated however it may be manipulated, wherein the pendant, key, or operating lever is not only of insulating material but also completely houses and covers all metallic parts of the switch operating mechanism so that there are no exposed metal screws, fittings, or other elements with which the hand of the person can come in contact.

Another object is the provision in a side wall lighting fixture of a pendant, key, or operating lever which has an improved connection to the switch operating member which it covers and houses, and, also, is constructed at its inner end so as to cover and protect the metal end piece on the lamp socket or holder and to cooperate in a novel fashion therewith to form a close, yet flexible connection therewith and at the same time to enhance the exterior appearance or design of the entire fixture.

In an application filed October 27, 1925, S. N. 15,263, I have set forth the ornamental design represented by the side wall lighting fixture hereinafter described. The present application sets forth the mechanical construction involved in the switch operating means for said fixture.

In the accompanying drawings:

Figure 1 is a side elevation of the side wall

lighting fixture provided with my improvements;

Figure 2 is a vertical section;

Figure 3 is a horizontal section taken above the operating pendant or lever; and

Figure 4 is a detail end view showing the housed fastening screw.

The side wall lighting fixture has a base or back plate 1, and a socket or holder 2, formed in a single piece, preferably of porcelain. The socket 2 contains the electric lamp socket 3 which is anchored at its lower end by the member 4, the latter being received in the cavity 5 in the bottom of the socket 2.

The lamp socket 3 contains a snap switch 6 which is opened or closed on alternate movements of a so called "universal" operating device 7. The universal operating device 7 may be of a type at present well known or of any construction and does not enter into my invention, except in its relationship to the improvements which will now be described.

The universal operating device 7 disclosed has a metal lever 8 connected to the pull chain 9 by a screw 10, but may be otherwise constructed and arranged.

My improved insulating pendant operating lever 11 is preferably of insulating material throughout and may be formed of porcelain to match the appearance and color of the fixture. The design represented by the fixture may be continued on the pendant 11 as set forth in my design of Serial No. 15,263, but this is not essential to the present invention. The pendant 11 is hollow to accommodate the metal lever 8 and it has a groove 12 which receives the projecting part of the screw 10. The upper end of the pendant 11 has a cavity 13 which receives the member 4

that attaches the lamp socket 3 to the fixture, thus covering and protecting or housing said member 4 and at the same time enabling the margin 14 of the cavity 13 to fit snugly against the bottom of the outer holder or socket 2 on the fixture and to serve as a fulcrum for said pendant 11 regardless of the direction in which said pendant is moved or flexed. The pendant 11 is therefore mounted in a universal manner to take advantage of the uni-

versal switch movement with which it is combined.

The end of the metal lever 8 has a screw threaded opening 15. The lower end of the pendant 11 is provided with a cavity 16 and an opening leading therethrough to the hollow interior of the pendant. A fastening screw 17 has its shank extending through said opening and screwed into the screw threaded opening 15. The head of the screw 17 is countersunk and completely housed by the cavity 16.

On detaching the screw 17, the pendant 11 may be removed to afford access to the lever 8.

15 The switch action draws upwardly upon the pendant 11 and normally keeps the margin 14 thereof against the lower end of the holder or socket 2.

When the pendant 11 is pressed laterally, 20 the switch is operated, regardless of the direction in which said pendant is pressed. On the release of the pendant it immediately resumes its normal position, drawn against the lower end of the socket 2.

25 The cooperation of the member 4 with the cavity 13 insures the centering of the pendant when it is released.

All of the metallic parts are completely housed by the pendant 11 and even the screw 30 17 is wholly unexposed on the surface of said pendant, the metal part 4 also being covered and protected by the upper end of the pendant 11.

What I claim is:

35 In a side wall lighting fixture having an upright socket or holder, the combination with a lamp socket and a switch carried by the holder of the fixture, and the means for securing said lamp socket to the holder, of switch 40 operating means extending through the bottom of the said fixture holder from the exterior to the interior thereof, an insulating pendant operating lever extending below the fixture holder and forming a continuation 45 thereof and having its upper end closely fitting the bottom of the holder and also universally fulcrumed thereat so that it may rock laterally in any direction, said pendant operating lever covering and protecting the means 50 for securing the lamp socket to the holder and being connected to the switch operating device and wholly housing that part thereof which lies outside the fixture holder.

In testimony whereof I affix my signature.

ROY W. SCHWEIKER.
